DESIGN FOR A ROTARY FLOOR TREATING MACHINE

Hamilton C. Chase, Sierra Madre, Calif., assign-
or to Hubert H. Peterson, Arlington, Va.

Application May 25, 1939, Serial No. 85,203

Term of patent 14 years

To all whom it may concern:

Be it known that I, Hamilton C. Chase, a citizen of the United States, residing at Sierra Madre, California, have invented a new, original, and ornamental Design for a Rotary Floor Treating Machine, of which the following is a specification, reference being had to the accompanying drawing, forming part thereof.

The figure is a perspective view of a rotary

floor treating machine, showing my new design. The other side is substantially as shown in the figure. The dominant features of my design reside in the portions shown in full lines.

I claim:

The ornamental design for a rotary floor treating machine, substantially as shown and described.

HAMILTON C. CHASE.
